(57) **CLAIM**

The ornamental design for a water pitcher, as shown in the drawings.

DESCRIPTION

FIG. 1 is a left rear perspective view of a water pitcher of the present invention;

FIG. 2 is top view thereof;

FIG. 3 is bottom view thereof;

FIG. 4 is a left side view thereof;

FIG. 5 is a right side view thereof;

FIG. 6 is a front view thereof; and,

FIG. 7 is a rear view thereof.

The broken lines in the drawings are included for the purpose of illustration and form no part of the claimed design.
